William R. Rogers
Design for Labels on Bottles or Tanks.
Patented Aug. 7, 1855

Des. 717

William A. Rogers, of Decatur, Ala.
Letters Patent No. 717 - Dated Aug. 7th 1855

The schedule referred to in these Letters Patent and making part of the same

To all whom it may concern: Be it known that I, W. A.

A. Rogers, of the Town of Decatur, County of Morgan, State of Alabama, have invented or produced a new and original design for labelling Jars, and Bottles with Gold or Silver leaf, and I do hereby declare that the following is a full and exact description of the same.

The top is inclined to be somewhat rounding, being brought to a small point at the center of the same and being brought to a point at the bottom. Immediately under the point above is a space in which there is an Eagle with the wings extended. Just below this is still a larger space designed for letters. On each side of the design, on the outside ranging near the centre, are two turned points, with two small open spaces in each. Below on either side of the design, are two turns, near each of which there is also an open space there is a border extending around that portion of the design intended for the letters, leaving above and below the same permanent.

What I claim as my invention is the construction of the design, and the fashioning of the letters, and the marking out of the same so as to leave them on the glass in a permanent form.

witnesses,

J. D. Johnston, } W. A. Rogers.
Henry B. Ross. }
